UNITED STATES PATENT OFFICE.

JESSE TAYLOR, OF GARDEN CITY, KANSAS.

DESIGN FOR A BUTTON OR BADGE.

SPECIFICATION forming part of Design No. 21,274, dated December 29, 1891.

Application filed October 8, 1891. Serial No. 408,161. Term of patent 3½ years.

To all whom it may concern:

Be it known that I, JESSE TAYLOR, a citizen of the United States of America, residing at Garden City, in the county of Finney and State of Kansas, have invented and produced a new and original Design for a Campaign Button or Badge, of which the following is a specification, reference being had therein to the accompanying drawing.

10 The figure of the drawing represents a front or face view of the design.

The several features of my design consist of a button or badge-pin circular in form, as shown in the accompanying drawing.

15 A is the front or face view of the button, circular in form. In the center of the button is a five-pointed star B, with a space for an

incription in the center of the star. The field of said button is divided into three equal divisions, with spaces for inscriptions 20 in each division, by radial lines a, two of which lines pass into parallel edges of the star, and the remaining line passes into the angle formed by the meeting of the opposite edges of said star. 25

What I claim is—

The design for a badge or button herein shown and described.

In testimony whereof I affix my signature in presence of two witnesses.

JESSE TAYLOR.

Witnesses:

FRANK B. APPERSON,
L. C. ROHRBOUGH.
